BINDER

Robert B. M. Taylor, Newark, N. J., assignor, by
mesne assignments, to Paralex Corporation,
Newark, N. J., a corporation of New Jersey

Application May 21, 1935, Serial No. 22,495

2 Claims. (Cl. 281—25)

The invention relates to binders, and more particularly to a binder of the type using a spirally wound wire, succeeding convolutions of which pass through a line of spaced openings in the 5 leaves of a book.

Binders of this general type are now being extensively used, notwithstanding that they have certain objectionable characteristics. With such binders, the spiral is assembled in the book structure by turning the spiral while threading it through the openings in the leaves, and the spiral ordinarily is free to turn after the assembly of the book and while it is in use.

With such spiral binders, every portion of each 15 coil or convolution has a pitch axially of the spiral, so that with a reversal or turning of the leaves of a book, each leaf has a trend, or component of movement axially of the spiral. This movement, if the leaf be held firmly in the hand 10 during the turning thereof, may tear the paper adjacent the openings therein, or adjacent some of said openings.

Various expedients have been proposed to prevent accidental turning of the spiral such as by 20 so forming the ends thereof as to prevent their passing through the openings in the leaves, or to engage some other portion of the binding in a manner to prevent such turning.

With the above conditions in mind, I have proposed 25 a binder embodying therein a binding wire which is not of itself a spiral but consists of a spiral so modified in form as to prevent accidental turning thereof in an assembled book. The original spiral form of the binder is so distorted or 30 warped as to each convolution thereof as to bring that portion of each convolution upon which the leaves are mounted into a substantially true circular form and in a plane radially of the axis of the binder wire, so that in turning the leaves 35 they will have no substantial component of movement axially of the binder wire.

Furthermore, in a binder embodying the invention, the extent of projection of the binder wire beyond the back of the bound book is reduced to 40 a minimum, thus obviating what is recognized as a serious objection to the so-called spiral binding.

The binder of the invention is particularly adapted to an inexpensive class of bindings, since 45 spirally wound wire may be economically produced and the labor cost in deforming the original spiral and in assembling a book structure is low.

The invention consists primarily in a binder 50 embodying therein a plurality of leaves each

having a series of spaced registering openings therethrough, and a metal binder wire threaded through said openings, said binder wire having a plurality of convolutions affording a sequence of arcuate portions threaded through the openings 5 in said leaves, and having a portion of each convolution flattened to afford a sequence of obliquely extending straight portions connecting the ends of adjacent arcuate portions, said connecting portions being of a length greater than a chord 10 of an arc of said arcuate portions extending between the ends of adjacent arcuate portions; and in such other novel features of construction and characteristics as are hereinafter set forth and described, and more particularly pointed out in 15 the claims hereto appended.

Referring to the drawing,

Fig. 1 is a longitudinal section of a book embodying therein the binder of the invention;

Fig. 2 is a section on the line 2—2 of Fig. 1;

Fig. 3 is a fragmentary portion of the back of a book embodying a modified form of the binder;

Fig. 4 is a section on the line 4—4 of Fig. 5; and

Fig. 5 is a longitudinal section of the book shown in Figs. 3 and 4.

Like numerals refer to like parts throughout the several views.

In the embodiment of the invention shown in Figs. 1 and 2 of the drawing, the top cover of the book is shown at 10, the bottom cover at 11 and the back board at 12. The covers 10 and 11 are loosely hinged to the back board 12, so that when the book is open, said back board will lie flat.

The book embodies therein collated leaves 13, 35 each having a series of spaced openings 14 therein registering with the openings of all the other leaves. Secured to the back board 12 is a transversely arched strip 15 of a length approximating that of the back board. The strip 15 may be secured to the back board in any desired manner, although I preferably employ a hollow rivet 16 permitting pivotal movement of the strip. At the end of the strip opposite to the point of its attachment to the back board, is an opening 17 45 by means of which this end of the strip may be secured in relation to the back board by a detachable fastener 18 having foldable tongues and known in the trade generally as a McGill fastener.

Threaded through the openings 14 of the collated leaves 13 is a binder wire. This binder wire originally is made in spiral form, but in the assembly of a book by means thereof, is so distorted or warped as to destroy its original form and provide therein a sequence of spaced sub-

stantially true circular or arcuate portions threaded through the openings in said leaves and upon which the leaves have turning movement, and a sequence of oblique straight portions connecting the ends of adjacent circular or arcuate portions adjacent the back board 12 upon which the leaves have no turning movement. The true circular or arcuate portion of each convolution of the binder wire is shown at 19 and the oblique straight connecting portion is shown at 20.

The oblique straight connecting portions 20 are formed by straightening or flattening a portion of each convolution of the original spiral.

In the embodiment of the invention shown in Figs. 1 and 2, the oblique straightened portions 20 include about 90° in arc of the original circle of the convolution. During the straightening or flattening operation the ends of the arcuate portions 19 with which the oblique portion is connected have two movements imparted thereto, one outwardly of the axis of the coil, and one longitudinally or axially thereof, the effect of this compound movement being to distort or warp the arcuate portion in a manner to substantially eliminate the original pitch thereof and thus eliminate the spiral trend of that portion of the binder wire which engages the leaves. With this condition, the spacing of adjacent arcuate portions is effected by the obliquely extending connecting portions 20.

Describing the condition geometrically, the oblique portions 20 form a chord of a circle of greater diameter than the original diameter of the convolutions of the spiral. The straightening of the wire, by reason of the increased length of the oblique portions 20, as compared with a chord of the arc of the original spiral so straightened, has a laterally and longitudinally spreading action upon succeeding arcuate portions, but in opposite directions. Thus, each arcuate portion has one end thereof move in one direction by one oblique portion, and the other end thereof moved in the opposite direction by the adjacent oblique portion. This imparts a sort of twist to each arcuate portion which has the effect of bringing it into a substantially true plane radially of the axis of the original spiral. If only 90° in arc be straightened, the arcuate portion 19 will have substantially no axial trend or pitch. If somewhere between 90° and 120° in arc be straightened, absolute accuracy in the elimination of any pitch in the arcuate portions may be secured. Accuracy, however, is not essential since the size of the openings 14 will allow sufficient play to avoid any noticeable axial component of movement of the leaves when turning them if the arcuate portions have a very high pitch. If, however, more than 120° in arc are included in each straightened or flattened portion 20, each arcuate portion will have a reverse pitch as compared with the pitch of the wire in the original spiral. The number of degrees in arc of each convolution of the spiral which have to be flattened or straightened will vary with the pitch of the original spiral or with the distance between succeeding convolutions thereof.

The straightened or flattened portion 20 of each convolution in addition to distorting or warping the portions of the original spiral so as to form substantially true arcuate portions 19 having substantially no axial pitch, will extend in a plane parallel with the back board 12 and the edge of the leaves 13 adjacent the openings 14 and close to said back board. If no back

board be used, the extent of the projection of this portion of the binder wire beyond the edges of the leaves adjacent said openings 14 is minimized.

Referring to the embodiment of the invention shown in Figs. 3 to 5, the construction of the binder wire is identical with that heretofore described. The book cover, however, in this form of the invention is composed of flexible material throughout, the bottom cover 10a, the top cover 10 11a and the back portion 12a being formed of one sheet of flexible material. The back portion 12a has openings 12b and 12c therethrough adjacent the top cover 11a and the bottom cover 10a, these openings being spaced apart lengthwise of said back portion, the same distance as the openings 14 of the leaves of paper.

In this embodiment of the invention, in addition to the functions above stated, the flattened or straightened portions 20 of the binder wire serve to spread the back portion 12a, since they are exposed outwardly of said back portion and are in close abutting relation thereto. The back portion cannot collapse inwardly of the binder wire.

In the assembled structure as shown in Figs. 3 to 5, a binder is provided having a substantially flat rigid back, notwithstanding that the back portion 12a may be of highly flexible material.

In the form of the invention shown in Figs. 1 and 2, the binder wire in spiral form is threaded through the openings 14 in the collated leaves 13, by turning a spirally wound wire and the passing of the end of this wire successively through the series of spaced openings 14. When the spiral wire is in the proper position, the portion of each convolution diametrically opposite the portion engaging the sheets, is flattened by means of suitable tools, thus producing the straight obliquely extending connecting portions 20 between succeeding circular or arcuate portions. This straightening or flattening of the wire has an elongating effect in the portion of the wire between succeeding arcuate portions, thus imparting axial movement to the portion of adjacent convolutions of the wire engaged with the leaves, but in opposite directions so as to secure the distorting, warping or twisting effect above referred to.

In all spiral binders, the binding wire must be of a diameter which will afford space within each convolution to permit the turning of the leaves, and this space affords adequate clearance for the anvil of the straightening tool above referred to.

The manner of binding the book in the form of the invention shown in Figs. 3, 4, and 5 is the same as heretofore described, with the exception that the cover is associated with the leaves before the flattening or straightening of the binding strand.

In the form of the invention shown in Figs. 1 and 2, to associate the cover with the leaves, it is merely necessary to slip the strip 15 within what may be termed the coils of the binding strand, and then fasten the free end of this strip to the back board by means of the fastener 17.

In the embodiment of the invention shown in Figs. 1 and 2, refills may be readily employed. In the form of the invention shown in Figs. 3 to 5, the binding is a permanent binding, although this form of the invention may be used as a refill for the form of the invention shown in Figs. 1 and 2.

In both forms of the invention shown, the oblique straight connecting portions 20 of the

binder resist any turning of the binding wire irrespective of the manner of associating the cover with the leaves.

The number of degrees in arc which are straightened or flattened is dependent largely upon the pitch of the original convolutions of the spiral, which pitch determines the spacing of succeeding spirals from each other. Ordinarily, the pitch of the convolutions is such as to space them apart from about one-quarter to one-half of an inch, and the axial movement imparted to the end of any convolution will amount to less than one-half of the increase in length of the flattened or straightened portion 20. This is due to the obliquity of this portion 20, and the distortion or warping of succeeding circular or arcuate portions 19 thereby. The spacing of succeeding convolutions of the original spiral may be so great as to prevent the securing of the desired final structure and still have an operative binder. When flattening or straightening the portions 20, the space between the arcuate portions 19 may be slightly increased as compared with the spacing of the convolutions of the original spiral, but in threading the spiral through the openings 14, the spiral may be expanded so that the subsequent flattening or straightening of the portions 20 will merely give a permanent set to the wire binder, the leaves 13 preventing excessive increase of the distance between succeeding arcuate portions 19.

It is not my intention to limit the invention to the precise details of construction shown in the accompanying drawing, it being apparent that such may be varied without departing from the spirit and scope of the invention.

Having described the invention, what I claim as new and desire to have protected by Letters Patent, is:—

1. A binder embodying therein a plurality of leaves each having a series of spaced registering openings therethrough, and a metal binder wire threaded through said openings, said binder wire having a plurality of convolutions affording a sequence of arcuate portions threaded through the openings in said leaves, and having a portion of each convolution flattened to afford a sequence of obliquely extending straight portions connecting the ends of adjacent arcuate portions, said connecting portions being of a length greater than a chord of an arc of said arcuate portions extending between the ends of adjacent arcuate portions. 5
2. A binder embodying therein a plurality of leaves each having a series of spaced registering openings therethrough, and a metal binder wire threaded through said openings, said binder wire having a plurality of convolutions affording a sequence of arcuate portions each being contained within a plane radially of the axis thereof, threaded through the openings in said leaves, and having a portion of each convolution flattened to afford a sequence of obliquely extending straight portions connecting the ends of adjacent arcuate portions, said connecting portions being of a length greater than a chord of an arc of said arcuate portions extending between the ends of adjacent arcuate portions. 10
